(57) CLAIM

The ornamental design for a chin protector for a protective face shield, as shown and described.

DESCRIPTION

FIG. 1 is a front perspective view of a first embodiment of a chin protector showing my new design;

FIG. 2 is a front view thereof;

FIG. 3 is a rear view thereof;

FIG. 4 is a right side view thereof, the left side view being a mirror image thereof;

FIG. 5 is a top view thereof;

FIG. 6 is a bottom view thereof;

FIG. 7 is a perspective view thereof, shown in a used condition with a protective face shield which is shown in broken lines;

FIG. 8 is a front perspective view of a second embodiment of a chin protector showing my new design;

FIG. 9 is a front view thereof;

FIG. 10 is a rear view thereof;

FIG. 11 is a right side view thereof, the left side view being a mirror image thereof;

FIG. 12 is a top view thereof;

FIG. 13 is a bottom view thereof; and,

FIG. 14 is a perspective view thereof, shown in a used condition with a protective face shield which is shown in broken lines.

The broken lines shown in the drawings represent portions of the chin protector for a protective face shield that form no part of the claimed design.
